CLIP

Bernard Yellin, Chicago, Ill.

Application October 9, 1956, Serial No. 614,852

2 Claims. (Cl. 24—259)

2

when it is desired to insert the clip on a rod such as rod 26, the legs 20 of the clip are manually engaged as shown in Fig. 2 and spread apart and the opening 22 is inserted on the end of the rod and the clip is pushed upwardly on the rod to the point desired.

The arcuate shaped opening 24 on each side will surround a portion of the rod and when the legs are released they will engage the rod and in effect bite into the rod to maintain the clip in position on said rod. By spreading 10 the legs the clip may be moved to any position on the rod or may be removed therefrom.

Figs. 1 and 3 show the application of this invention for retaining various parts. Fig. 1 shows a cage member generally designated at 30 which has vertical rods 26 which

15 extend into openings 32 formed in a platform or base 34. The vertical rods 26 extend below the base or platform so that the clips 10 forming this invention may be inserted thereon. The top of the clips rest against the underside of the base as shown to secure the cage to the base. Suitable legs 36 may be provided for supporting the base.

20 Fig. 3 shows the rod 26' provided with a beaded portion 27. The rod being inserted in the opening 32' through the top of the base 34' and being secured to the base by means of the clip member 10 as shown.

25 With this invention various components or parts may be secured to a stud or rod by means of the clip and may be readily removed by removal of the clip.

It will be understood that various changes and modifications may be made without departing from the spirit and scope of the appended claims.

I claim:

1. A clip for securing a rod to an object, said clip comprising a top portion having a central flat top portion provided with a central opening to receive a rod, curved 35 upwardly extending end portions at the opposite ends of the flat top portion and extending above the top of the flat top portion for engaging the surface of the object and for spacing the central flat top portion therefrom, legs continuing from said end portions, said legs each being substantially of V shape, each leg having an arcuate recess, in the apex of the V of each of said legs and in vertical alignment with said opening and adapted to envelope a portion of the rod at the recess.

2. A clip for securing a rod to an object, said clip comprising a central flat top portion provided with a central opening to receive a rod, curved upwardly extending end portions at the opposite ends of the central flat top portion and extending above the top of the flat top portion for engaging the surface of the object and for spacing the central flat top portion therefrom, legs continuing from said end portions, said legs first extending inwardly towards each other and then having a reversely bent portion extending downwardly and outwardly, each of said legs at said bent portion being provided with a recess, in vertical alignment with said opening and each of said legs being adapted to envelope a portion of the rod.
